UNITED STATES PATENT OFFICE.

JOSÉ GALLEGOS, OF SAN JOSÉ DE GUATEMALA, GUATEMALA.

TELEGRAPH RECEIVER OR RELAY.

SPECIFICATION forming part of Letters Patent No. 626,606, dated June 6, 1899.

Application filed December 24, 1898. Serial No. 700,242. (No model.)

To all whom it may concern:

Be it known that I, JOSÉ GALLEGOS, a citizen of the Republic of Guatemala, and a resident of San José de Guatemala, in the Republic of Guatemala, have invented new and useful Improvements in Telegraph Receivers or Relays, of which the following is a full, clear, and exact description.

My invention relates to electromagnetic circuit-closers of the class known as "relays," such as used principally in telegraphy, and has for its object to provide a relay having a powerful magnetic effect, the strength of which is readily adjustable.

To this end my invention consists in the particular construction and arrangement of parts defined in the appended claims, the preferred embodiment of my invention being shown in the accompanying drawings, in which—

Figure 1 is a plan of the improved relay. Fig. 2 is an elevation showing one of the line-magnet spools in section, and Fig. 3 is an end view from the side on which the adjusting-screw H is arranged.

On a suitable base I are secured supports G, in which are mounted to slide longitudinally the spools A of the line-magnet, the adjustment being effected by means of a screw H, journaled in a stationary bracket H' and having an enlarged head H², fitting into a recess of a lug B', projecting from the cross-bar B², which connects the cores B of the line-magnet. The said cores are provided at one end with bent members or crank members B³, terminating in pole-pieces B⁴, extending parallel to the axes of the cores. These pole-pieces and crank members are preferably sheathed with rubber J except at their extremities. The crank members B³ are mounted to turn about the axes of the respective cores B, so that the distance from one pole-piece to the other may be readily varied. Obviously this might be effected by having the crank members B³ turn upon stationary cores B with sufficient friction to prevent an accidental movement of said members. I prefer, however, to make the crank members rigid with the corresponding cores, as shown, the cores turning in the spools with sufficient friction to prevent an accidental rotary movement, and in such case a longitudinal move-

ment of the cores B relatively to the spools A is prevented by making the cores with shoulders engaged by the ends A' of the spools A. 55

Adjacent to the pole-pieces B⁴ is arranged the armature C, suspended at C' from a support D, which is connected with one pole of the local source of current—for instance, a local battery. The armature C is adapted to 60 swing, as usual, between two adjustable points F', one of which at least is connected with the other pole of the local battery through the medium of the support F, while the other point F' may serve as a stop only. To keep 65 the armature in a predetermined position when not attracted by the magnet A B, I provide a spring K, passing through a ring D' on the support D and secured by means of a string or wire K' to a spindle L, rotatable in 70 the post L', so that by turning the spindle and winding the flexible connection K' thereon more or less the tension of the spring K may be adjusted.

It will be observed that by swinging the eccentric pole-pieces B⁴ on the axes of the respective cores I not only adjust the distances of said pole-pieces from each other, but I also vary the distance of said pole-pieces from the pivot C' of the armature C, and I am thus enabled to increase or decrease the leverage of the magnetic force exerted upon the armature. The pole-pieces while being adjusted move in a plane perpendicular to the axes of the cores or with respect to the armature in a plane 85 perpendicular to that in which the armature moves.

Having thus described my invention, I claim as new and desire to secure by Letters Patent—

1. The combination of the movable armature, the electromagnet having an end or pole movable in a plane perpendicular to that in which the armature moves, and a circuit-closer controlled by the movement of the armature. 95

2. The combination of the electromagnet being a core and an eccentric pole-piece mounted to turn about the longitudinal axis of the core, the armature pivoted about an axis perpendicular to that about which the 100 pole-piece may turn, and a circuit-closer controlled by the movement of the armature.

3. The combination of the rotatable core carrying a pole-piece located off the axis of

rotation, the armature pivoted about an axis perpendicular to the core's axis of rotation, and a circuit-closer controlled by the movement of the armature.

5 4. The combination of the movable armature, the electromagnet having a core, and a crank member at the end thereof carrying a pole-piece projected parallel to the core, said

crank member being movable about the axis of the core, and a circuit-closer controlled by the movement of the armature.

JOSÉ GALLEGOS.
